UNITED STATES PATENT OFFICE.

GEZA HORVATH, OF HIGHLAND PARK, MICHIGAN.

SPEED-CONTROLLING DEVICE FOR VEHICLES.

1,377,964.

Specification of Letters Patent. Patented May 10, 1921.

Application filed December 15, 1919. Serial No. 345,013.

To all whom it may concern:

Be it known that I, GEZA HORVATH, a citizen of the United States, residing at Highland Park, in the county of Wayne and State 5 of Michigan, have invented certain new and useful Improvements in Speed-Controlling Devices for Vehicles, of which the following is a specification, reference being had therein to the accompanying drawings.

This invention relates to the fuel supply system of an internal combustion engine, and has special reference to a carburetor and appurtenant parts which permit of an engine being accelerated and the speed of the engine 10 controlling automatically the supply of fuel thereto, to the most economical point under various speed and load conditions.

My invention aims to furnish a carburetor with a valvular fuel feed member that may 15 be easily adjusted to increase the supply of fuel to the carburetor, so that the engine will be accelerated and simultaneous with the adjustment of the valvular seat member an indicator will be actuated to indicate the 20 condition of the explosive mixture being supplied to an engine, for instance, whether the mixture is lean or rich.

My invention further aims to provide a carburetor with a governor actuated valvular member which is adapted to prevent 25 excessive speeding of the engine, and, through the medium of an indicator, show the speed of the engine.

My invention further aims to provide 30 mechanism that may be advantageously associated with an internal combustion engine of any type, but especially forming the power plant of an automobile or similar vehicle, so that greater efficiency may be obtained from the engine with a minimum expenditure of fuel, because the fuel supply is automatically increased or decreased to the most efficient point under various load and speed conditions.

My invention will be hereinafter considered and then claimed and reference will now be had to the drawing, wherein—

Figure 1 is an end elevation of an internal combustion engine, partly broken away and 5 more or less diagrammatic, showing a carburetor and associated parts relative to the engine, the carburetor being in section and the mechanism partly broken away, and

Fig. 2 is a front elevation of an indicator 10 forming part of the mechanism.

In the drawing, the reference numeral 1

denotes an internal combustion engine having an intake manifold 2 and suitably connected to said intake manifold is the upper curved or elbow end 3 of a carburetor body 4, said carburetor having an air intake connection 5 and a float chamber 6. In the curved or elbow end 3 of the carburetor body 4 is the usual throttle 51 and adapted to adjust the throttle is a flexible member 52 which will be hereinafter considered. The float chamber 6 is of a conventional form having an offset portion 7 adapted to receive liquid fuel from a tank or other source (not shown). In the offset portion 7 of the float chamber 6 is a valve 8 actuated by a float 9 within the chamber 6 to maintain a constant level of fuel within the chamber, said float and valve being of the ordinary type.

The carburetor body 4 is provided with a depending sleeve 10 having a spiral slot 11 and rotatable and slidably in said sleeve is a valvular member 12 having a pin 13 extending into the spiral slot 11, so that the valvular member 12 will be raised and lowered in the sleeve 10 when said valvular member is partially rotated. The valvular member 12 has its annular groove and transverse passage 14 communicating with a passage 15 leading to the float chamber 6 and axially of the valvular member 12 is a passage 16 leading to a valve seat 17 in the upper end of the valvular member 12, the passages 15, 14 and 16 admitting liquid fuel from the float chamber 6 to the carburetor body 4.

On the lower end of the valvular member 12 is a pinion 18 meshing with a rack 19 slidably in a bearing bracket 20 connected to the crank case of the engine 1 or suitably attached to any support in proximity thereto. The rack 19 is normally held in a retracted position by the retractile force of a spring 21 connected to said rack and said rack may be shifted by a rod 22 connected to a treadle or lever 23, which when actuated is adapted to partially rotate and raise or lower the valvular member 12. The treadle or lever 23 is connected to the flexible member 52 so that the accelerator treadle may adjust the throttle, as is the usual practice.

The rack 19 also meshes with a pinion 24 at the lower end of a flexible shaft 25 supported by the bracket bearing 20, said flexible shaft extending to an indicator 26 where it is adapted to impart movement to a pointer 27 in front of a dial 28 calibrated to indicate the extent of vaporized fuel or an

explosive mixture supplied by a carburetor. Adjustable in the elbow connection 3 of the carburetor body 4 is a valve rod 29 having a valve 30 movable to and from the seat 5 of the valvular member 12, said valve rod having the threaded portion 31 in engagement with the elbow connection 3 of the carburetor body 4 and at the upper end of said valve rod is a handle 32 which permits of 10 said valve rod being manually adjusted.

Frictionally held on the valve rod 29 and adapted to rotate said valve rod is a pinion 33 meshing with a rack 34 slidable in a bracket bearing 35 carried by the engine 1. 15 The inner end of the rack 34 is fixed to a governor spool 36 slidable on a shaft 37 journaled in a bearing 38 carried by the engine 1. Mounted on the shaft 37 is a gear wheel 39 having its hub portion provided 20 with a governor bracket 40 and pivotally connected to said governor bracket are governor arms 41 engaging the spool 36, said governor arms being connected by a coiled retractile spring 42 adapted to restore said 25 arms to normal position after having been actuated by centrifugal force.

Meshing with the gear wheel 39 is a gear wheel 43 mounted on a shaft 44 journaled in the bracket 38 and a bracket 45 at the forward end of the engine 1. The shaft 44 is adapted to be driven by a sprocket chain 46 or other power transmission device from a driven shaft 47 of the engine 1.

Meshing with the rack 34 is a pinion 48 35 carried by a flexible shaft 49 supported by the bracket bearing 35, said flexible shaft extending to the indicator 26 to operate a pointer 50 movable in front of the dial 28 of said indicator, said dial being calibrated 40 to indicate the revolutions permitted of the main engine shaft.

Since the valve rod 29 may be manually 45 adjusted relative to the pinion 33, it is possible to set the valve 30 relative to the valvular member 12 so that there will be a predetermined passage for fuel from the valvular member 12 into the body of the carburetor to commingle with air admitted at the connection 5 and provide an explosive mixture.

50 The passage between the valvular member 12 and the valve 30 may be such as to admit a sufficient quantity of fuel for engine idling purposes. Then, if it is desired to accelerate the engine, it is only necessary to press upon 55 the treadle 23 when the valvular member 12 will be rotated and lowered relative to the valve 30, thereby increasing the area of the passage so that a greater quantity of fuel will be admitted to the carburetor body for 60 vaporizing purposes. The additional fuel will increase the speed of the engine and the accelerator may be used either when warming up, starting or when encountering grades or rough sections of road. The volume or 65 quantity of fuel may be determined by ob-

serving the indicator 26 and the accelerator may be used to provide a rich or lean mixture as desired.

To prevent excessive speed of the engine, the valve 30 is placed under control of the 7 governor operated from the drive shaft 47 of the engine, and when the speed of the engine is above normal the centrifugal force of the governor causes the rack 34 to be shifted and the valve 30 lowered to constrict 7 the passage between said valve and the valvular member 12, thereby reducing the supply of fuel to the carburetor until the engine obtains normal speed as will show by the indicator 23.

In order that the operation of my device may be fully understood, I will assume that my automobile is standing still with the engine idling by reason of the throttle being partly open, as shown in Fig. 1, and the valvular member in spaced relation admitting sufficient fuel to sustain the engine at idling. On starting my engine I press on the treadle 23 to accelerate the engine by lowering the valvular member 12 relative to the valve 30, admitting a greater quantity of fuel with the throttle open. It is obvious that the engine will immediately pick up its speed and the governor will be effected by having its governor arms separated thereby causing 9 the valve 30 to be lowered. This will take place even though the accelerator is released, thus allowing the engine to operate with a greater volume of explosive mixture, which is not as rich as when the accelerator 1 was initially operated. It is now apparent that the valve 30, in controlling the fuel, accomplishes the reverse of the accelerator, that is, the valve 30 reduces the supply of fuel whereas the accelerator is adapted to increase the supply. Further assuming that

I am traveling on a level road and encounter a grade, it is obvious that the engine has a greater duty to perform, and consequently the governor is actuated to open the 1 valve 30 and admit more fuel, so that the explosive mixture will be richer while the greater load is on the engine, but immediately upon the grade being ascended the load on the engine is reduced and consequently the speed, so that the valve 30 is lowered to decrease the supply of fuel and consequently the richness thereof, thereby restoring the engine to normal fuel condition.

Supposing that a hill has been ascended 1 and there is a descent, it is apparent that the load on the engine is reduced with the governor causing the valve 30 to be closed and produce a very lean explosive mixture. Such condition will exist until the automobile reaches a level or another grade, when the accelerator may be used should it be desired to increase the speed of the engine. Under all conditions the governor actuated valve 30 is automatic in controlling the sup-

ply of fuel, and after an operator has once determined the best operating conditions for his automobile, it is easy to determine by the indicator when such conditions do not exist thus warning the operator that something is wrong with his machine or the fuel. It is now apparent that the device possesses "tell-tale" features that will permit of an operator checking up on the condition of the automobile compared to the best operating conditions obtained, and in my companion application, filed under even date I show an indicator that may be advantageously used in connection with a device of this kind.

15 It is thought that the operation and utility of the present invention will be apparent without further description, and I would have it understood that the structural elements are susceptible to such variations 20 and modifications as fall within the scope of the appended claims.

What I claim is:—

1. The combination of a carbureter body, a rotatable and slidable valvular member in 25 said carbureter body adapted to admit fuel thereto, means adapted to adjust said valvular member, an adjustable valve in said carbureter body movable to and from said valvular member, a governor actuated means for 30 adjusting said valve, and means adapted to indicate adjustment of said valve and valvular member.

2. The combination of a carbureter hav-

ing an adjustable valvular seat member, a rack and pinion for adjusting said valvular 35 seat member, a valve movable to and from said valvular seat member, a rack and pinion for adjusting said valve, and indicating means operated from said rack.

3. The combination of a carbureter body, 40 a rotatable and slidable valvular member in said body adapted to admit fuel thereto, a rack and pinion adapted to rotate said valvular member, treadle means adapted for shifting said rack, and indicating means op- 45 erated from said rack.

4. The combination of an engine having a carbureter, valvular members in the carbureter adjustable to and from each other and independent of each other, manually actuated means for moving and holding one of said valvular members to increase the speed of the engine by producing a rich fuel mixture, and an engine operated governor for moving the other member in proportion to 55 the speed of the engine, said governor operated member being further moved by excessive speed toward the first mentioned valvular member to produce a lean fuel mixture and a consequent reduction in speed. 60

In testimony whereof I affix my signature in the presence of two witnesses.

GEZA HORVATH.
